SHIPPING AND DISPENSING CARTON

John W. Kraus, Cleveland Heights, Ohio

Application April 1, 1950, Serial No. 153,389

1 Claim. (Cl. 222—457)

1
This invention relates to shipping and dispensing cartons, containers and the like and more particularly to cartons adapted for shipping and dispensing small articles such as, for example, nuts, bolts, fittings and the like.

In manufacturing establishments where small articles such as nuts, bolts, fittings and small parts are required in assembly operations it is customary to remove the articles from the container in which they are shipped into the factory and place them in boxes or bins at each workman's bench or in a stock or store room if used in small unit quantities. This procedure requires the construction of boxes or bins at the benches or stock or store room or the use of makeshift devices, and is unsatisfactory because parts may be lost or damaged while they are being transferred from their original cartons to the bins; furthermore, parts of different sizes may become intermingled and ordinarily the bins or boxes containing the parts on the workman's desk are not properly labeled.

According to the present invention, the above-noted difficulties are overcome by the provision of a shipping carton or container which may also be used on the workman's bench or in stock or store rooms or elsewhere as a dispensing bin or hopper thus making it unnecessary to provide special bins or boxes, keeping the parts clean and in proper order and providing convenient bins for the parts which are identified by the labels appearing on the cartons.

The general object of the present invention is the provisions of a shipping and dispensing container, carton or the like which provides a sturdy package for the parts during shipment and a convenient dispensing hopper or bin thereafter. Another object is the provision of such a carton or container which can be manufactured economically of conventional materials such as corrugated paper and the like.

Other objects and advantages of the invention will become apparent from the following description of preferred forms thereof, reference being made to the accompanying drawings in which Figure 1 is perspective of a corrugated paper carton made according to the invention and showing the carton in the position it takes when in use on a workman's bench; Figure 2 is a fragmentary perspective view of the end of the carton of Figure 1 showing the carton closed as it is during shipment; Figure 3 is a longitudinal sectional view through the carton 1; Figure 4 is a plan view of the blank employed in producing the carton in Figure 1; Figure 5 is an exploded perspective

2
view of the parts making up a modified form of the carton; Figure 6 illustrates the carton of Figure 5 in closed position, parts being broken away for convenience of illustration; Figure 7 is a perspective view of the carton of Figures 5 and 6 in position for use; Figure 8 is a longitudinal section of the hopper portion of the carton of Figure 7; and Figure 9 is a plan view of the blanks utilized in making the hopper portion shown in Figure 8.

Referring now to Figures 1 to 4 of the drawings a preferred form of carton embodying my invention is indicated in general at 10. This comprises a corrugated paper carton which may be of conventional construction except for the front end where the dispensing hopper is located. The carton 10 has a top wall 11, side walls 12 and 13, a bottom wall 14 and a rear end wall made up of flaps 15, 16, 17 and 18 (see Figures 3 and 4). The sides and rear of the carton may be reinforced with conventional paper tape reinforcements 20 and 21 if desired, or any other ordinary method of closure may be used.

At the front end of the carton, the construction of the top half may be conventional including a flap 22 formed integrally with the top wall 11; flap 22 is folded over the end of the carton and overlies the end flaps 23 and 24 which are formed integrally with the side walls 12 and 13 respectively. However, in order to provide a hopper or bin-like opening giving ready access to the articles within the carton when the carton is opened and positioned as shown in Figure 1, the construction of the lower half of the front end 30 of the carton is arranged to provide the hinged hopper flap 25 and wings 26 and 27 which define a hopper or bin when in open position.

In order to provide the hopper without requiring the use of any additional stock in making the carton, the bottom wall panel 14 of the blank extends forwardly as shown in Figure 4, terminating in the hopper flap 25 which is preferably of such size as to cover half of the end of the carton when the carton is closed, forming with the flap 22 a complete closure. Formed integrally with the hopper flap 25 are wings or side flanges 26 and 27. It will be noted that the blank is severed as indicated at 28 and 29 so that these wings or side flanges are separated from the side panels 12 and 13 and the flaps 23 and 24. In the assembled carton, wings are folded upwardly to lie at right angles to the flap 25 and parallel to the side walls 12 and 13; thus, the wings constitute the sides of the hopper provided by the flap 25.

In order to permit the hopper to be opened and closed readily and to retain the hopper flap 25 in an upwardly slanting position as shown in Figures 1 and 3, the edges of the wings 26 and 27 are cut in arcuate form as shown at 31 and 32 respectively, the arcs being struck about the intersections of the score line 33 and the score lines 34 and 35 respectively. The arcs terminate in radially extending stop portions 36 and 37 respectively; these stops engage the inner surface of the flaps 23 and 24 as shown in Figures 1 and 3 to limit the outward swinging movement of the hopper flap 25.

When the hopper flap 25 is opened and the carton properly positioned, a number of the articles contained in the carton tumble into the hopper where they are readily accessible. The articles feed in to the hopper automatically to replenish those withdrawn therefrom and ordinarily there is no overflowing of articles from the hopper. There is no difficulty in emptying the carton completely because the hopper opening extends from side wall to side wall of the carton and there are no shoulders or obstructions to trap articles within the carton. The hopper opening is shown as extending half way from bottom to top across the end of the carton in the drawings. This is the most economical arrangement because the flaps 22 and 25 are of the same length and there is no waste of material. However, for some purposes and for handling articles of various types it may be desirable to make the flaps 22 and 25 of unequal length thereby to either increase or decrease the size of the hopper as may be required. The carton may be initially filled from the rear end and thereafter sealed.

It will be noted that when the carton is in closed position as shown in Figure 2, the wings 26 and 27 lie flat along the interior of the walls 12 and 13 and thus do not materially reduce the capacity of the carton. The flap 25 completes the closure of the carton which may be sealed by a strip of paper reinforcing tape 39 if desired. In order to open the carton it is only necessary to slit the tape 39 at the center of the carton and swing the flap 25 outwardly and downwardly until further movement is arrested by the engagement of the stops 36 and 37 with the flaps 23 and 24. Thus when a workman needs a new supply of a given part it is only necessary to deliver a sealed carton of the parts to him. He thereupon places the carton in a convenient position upon his bench and opens it. The parts are then readily accessible to him, no parts have been lost and the parts are as clean as they were when they were shipped by the manufacturer. Ordinarily shipping cartons are labeled as indicated at 40, for example, to show their contents; such labels remain on the cartons, thus identifying the parts at all times. Instructions for opening the carton may be printed directly on the carton.

In Figures 5 to 9 of the drawings an adaptation of the invention to a conventional carton is shown. Here the carton 45 may be of any conventional construction while the hopper is provided by a separately formed hopper member indicated in general at 46. The carton proper is made up of top, side and bottom walls 47, 48, 49 and 50, a rear end wall 51 composed of flaps in the usual manner and a front end wall made up of flaps 52, 53, 54 and 55. The hopper member 46 fits snugly within the front portion of the carton 45 adjacent the front end wall and is

preferably secured in place by staples 57 (see Figure 6) and similar staples on the bottom of the container.

As shown particularly in Figures 5, 8 and 9 the hopper member 46 is made up of top, side and bottom walls 60, 61, 62 and 63. These are folded to provide a rectangular body adapted to be telescoped within the end of the carton 45 and the body is held in assembled position by tape 64 or by stitching or gluing. The bottom wall 63 has an integrally formed hopper flap 65 which corresponds to the flap 25 previously described. Wings 66 and 67 are joined to the ends of flap 65 and have arcuate portions 68 and 69 and stop portions 70 and 71, the wings being constructed in the same manner as wings 26 and 27 previously described.

In order to provide stops for engagement by the stops 70 and 71 the top wall 60 of the body of the hopper member has a front flap 72 formed integrally therewith, the flap 72 having wings 73 and 74 on either end thereof. These wings are adapted to be folded along score lines 75 and 76 so that the wings can extend rearwardly along the side walls 61 and 62 as shown in Figures 5 and 6, the wings being disposed between the side walls 61 and 62 of the hopper member and the side walls 48 and 49 of the carton when the parts are assembled. Score lines 75 and 76 are disposed outwardly of the edge 78 of the top wall 60 and the score line 79 so that the wings 73 and 74 will be properly positioned when the parts are assembled.

Flaps 80 and 81 extend from the side walls 61 and 62 of the hopper member and the flap is preferably stapled to flaps 80 and 81 by staples 82 thus holding the parts of the hopper member in assembled position as shown in Figure 5. Flap 81 may be cut away as shown in Figure 9 to provide material for the wing 73 of an adjacent blank.

It will be noted that when the hopper member 46 is telescoped into the carton the wings 66 and 67 are disposed between the side walls 61 and 62 of the hopper member and the side walls 48 and 49 just as the flaps 73 and 74 are. Thus the wings operate in the slot provided by the telescoping side walls. The radial stop portions 70 and 71 of the wings 66 and 67 engage the wings or flaps 73 and 74 to limit the outward movement of the hopper 65. Inasmuch as the wings 66 and 67 are disposed between the side walls of the hopper and the carton the wings are protected from contact with the articles within the carton; thus with this form of the invention the hopper can be opened and closed repeatedly without damage to the wings by reason of engagement with the articles within the carton.

In use of this type of carton embodying my invention the carton is filled from the rear end with the hopper member in place and sealed. When the carton reaches the workman's bench he merely opens the front end of the carton in the usual manner by slitting the tape 83 and opening the flaps 52, 53, 54 and 55 or by cutting the sealed end off entirely close to the scores between 47, 48, 49 and 50 and 52, 53, 54 and 55 respectively. Then it is only necessary for the operator to open the hopper member 65 whereupon the articles within the carton become readily accessible as in the previously described form of the invention.

This type of carton is stronger than the previously described modification because of its double end construction and has a further advantage

in that it can be repeatedly opened and closed without damage to the side flaps of the hopper. It is obviously slightly more expensive than the previously described form of invention.

From the foregoing description of the preferred forms of my invention it will be seen that I have provided shipping and dispensing cartons or containers that are capable of manufacture at reasonable cost and which provide important advantages in use. My cartons are essentially shipping containers in which no appreciable amount of space is lost by reason of the hopper construction and yet they provide convenient hoppers for dispensing and supplying articles where required. By the use of my cartons the necessity of special bins or hoppers at workmen's benches or elsewhere is prevented, intermingling of parts of different sizes is prevented, loss of parts is prevented and the parts are kept clean and in good condition.

Those skilled in the art will appreciate that various changes and modifications can be made in the invention without departing from the scope thereof. For example, changes may be made in design and proportions of the cartons to suit various purposes, and materials other than the corrugated paper illustrated herein may be employed in the manufacture of the cartons. It is therefore to be understood that my invention is not limited to the preferred forms described herein and that the scope of the invention is defined by the appended claim.

I claim:

In combination, a carton having side, top, bottom and end walls and a hopper member disposed within the carton adjacent one end thereof, said hopper member comprising a body portion having side, top and bottom walls and hav-

ing an open end and a closed end, the top and bottom walls of the hopper member engaging the top and bottom walls of the carton, the side walls of the hopper member being parallel to and spaced inwardly from the side walls of the carton, the closed end of the hopper member lying adjacent one end of the carton and comprising a hopper flap hinged to the bottom wall of the hopper member and adapted to close substantially half the end of the hopper member when in closed position, wings on the ends of the hopper flap disposed at right angles thereto and lying between the side walls of the carton and the side walls of the hopper member, an end flap for closing the other half of the end of the hopper member, and wings on the ends of said end flap extending into the space between the side walls of the hopper member and the side walls of the carton and disposed above the wings on the hopper flap, said hopper flap being adapted to be swung outwardly when said carton is open to provide a hopper for articles in the carton, the wings on the hopper flap constituting sides of the hopper and the wings on the hopper flap and the wings on the end flap having interengaging parts adapted to limit outward movement of the hopper flap.
